UNITED STATES PATENT OFFICE.

JOHN W. NEIL, OF CINCINNATI, OHIO.

AUTOMATIC PRESSURE-GOVERNOR.

SPECIFICATION forming part of Letters Patent No. 696,471, dated April 1, 1902.

Application filed June 24, 1901. Serial No. 65,741. (No model.)

To all whom it may concern:

Be it known that I, JOHN W. NEIL, a citizen of the United States of America, and a resident of Cincinnati, in the county of Hamilton 5 and State of Ohio, have invented certain new and useful Improvements in Automatic Pressure-Governors, of which the following is a specification.

The object of my invention is a pressure-regulator to be placed in the steam-line of an engine which automatically controls the amount of steam passing through it, so as to keep said amount in proportion to the pressure against which the engine is working, so 10 that against variations of pressure below a certain limit the engine will run at a uniform speed and cease to run when that limit is passed. This object is attained by the means described in the annexed specification and 15 illustrated in the accompanying drawing, in which the figure is a central vertical sectional view of a pressure-regulator embodying my invention in a form used for regulating a pump.

20 Valve-casing A, which is to be placed in a steam-pipe leading from a boiler into a steam-pump, has its inlet-opening a upon a higher horizontal plane than its outlet-opening a'. Within the upper end of cylinder A, between 25 openings a and a', is a piston-valve B, which consists of a cylinder with closed ends b and b' and longitudinal slots b² in its sides, extending from the upper end downward, leaving an imperforate portion b³ at the lower end, 30 which in the uppermost position of the valve registers with and closes the outlet-opening a'. Valve B is held in its upper position by a spring b⁴, pressing upward against b' with a pressure which may be regulated by screw 35 b⁵ in the lower end of casing A.

Upon the upper end of casing A is a cylindrical governing-chamber C, within which is a piston c, whose piston-rod c' extends through the upper head of cylinder A and is secured 40 to end b of valve B. A pipe c² forms communication between the upper end of governing-chamber C and the pressure against which the pump is discharging—as, for instance, the pressure in a tank (not shown) for hydraulic 45 elevators. The limit of the upper travel of valve B is regulated by a hand-screw c³ in the head of valve-chamber C, against which pis-

ton c abuts when the valve is in its uppermost position. Suppose valve-casing A to be interposed in a pipe conveying steam to a 55 pump and that the pump is working against a normal pressure in a tank wherein the degree of pressure is subject to change. Steam would enter through opening a, go through slots b² into cylinder B, and out through opening a', and thence to the pump. Now should the pressure in the tank be diminished this diminution of pressure is immediately conveyed to piston c, which allows spring b⁴ to carry valve B upward, so that imperforate 60 portion b³ of the valve lessens the size of discharge-opening a', and thereby diminishes the supply of steam to the pump in proportion to the diminution of pressure in the tank, so that the pump does not "run away." As the 65 pressure in the tank is raised again the pressure being conveyed to the top of piston c again lowers valve B to admit the desired amount of steam to the pump to run it against the increased pressure.

To keep the pressure in the tank below a certain limit, I employ the following means: Within the lower end of cylinder B is a secondary valve D, which consists of a cylinder of a length substantially equal to portion b³, 80 open at its upper end and closed at its lower end d, which has perforations d' in it to allow the steam to pass the under side of it, so as to make it a balanced valve. Extending from the lower end d through end b' of valve 85 B, through screw b⁵ in the lower head of casing A, and into a second governing-chamber E, which is secured to the lower end of casing A, is a stem d², which terminates within the chamber E in a piston e. Valve D is held 90 in its lower position within valve B by a spring d³, which surrounds stem d² between the end b' of valve B and a collar d⁴ upon stem d², by which the tension of said spring may be regulated. Entrance into the lower end of governing-chamber E is controlled by a valve e', 95 which may be set by means of spring e², so that it requires a certain pressure to open it. A pipe e² connects valve e' with the tank into which the pump is discharging. If the pressure in the tank exceed that at which spring e² is set, the pressure opens valve e', raises piston e and valve D, which contracts openings a' and diminishes the supply of steam to 100

the pump until the pressure in the tank falls below the limit, when valve D is returned by spring d^3 to its normal position to allow the steam to pass, as usual, to the pump.

5 It is of course obvious instead of having slots in the cylindrical valve B between the imperforate lower end and the upper end the intervening metal between said parts might be cut away entirely and the ends connected 10 by a rod or other means, so that the valve remained a balanced valve—that is, that the pressure of steam on the end b were counterbalanced by that upon end b' of valve B.

What I claim is—

- 15 1. In a pressure-governor for controlling fluids under pressure a valve-casing having its inlet-opening in a different horizontal plane from its outlet-opening, a valve within the case having adjacent to the outlet-opening an imperforate end portion to be carried over the outlet-opening to contract the same and an upper portion above the inlet-opening and connected to the imperforate end portion to balance a pressure thereon, a spring to hold 25 the valve in its normal position, and a channel for communicating the pressure to be controlled to the valve to move it when said pressure varies from that of the spring, substantially as shown and described.
- 20 2. In an automatic pressure-governor for engines the combination of a valve-case having its inlet-opening upon a higher horizontal plane than its outlet-opening, a cylindrical valve within the casing consisting of a lower 25 imperforate end portion adjacent to the outlet-opening an upper disk above the inlet-

opening and connected to the lower portion, a spring bearing upward against the valve, a governing-chamber upon top of the case, a piston within the chamber, a rod connecting 40 the upper end of the valve and the piston and channel for communicating the pressure against which the engine works to the piston, substantially as shown and described.

3. In a pressure-governor the combination 45 of a casing having its inlet-opening upon a higher horizontal plane than its outlet-opening, within the casing a hollow cylindrical valve having closed ends and longitudinal slots in its sides leaving an imperforate portion at its lower end adjacent the outlet-opening, a spring bearing upward against the valve, a second balanced valve within the lower end of said valve, a governing-chamber upon the upper and upon the lower ends of 50 the casing, pistons within the chambers, a rod connecting the upper piston with the first valve a second rod connecting the lower piston with the second valve, a valve controlling the entrance to the lower governing-chamber 55 which is to be opened only by a pressure exceeding a certain limit, and means for communicating the pressure of discharge to the piston within the upper governing-chamber and to the valve controlling the entrance to 60 the lower governing-chamber, substantially as shown and described.
